US00D562167S

(12) **United States Design Patent** (10) Patent No.: **US D562,167 S**
Petrucci (45) Date of Patent: **** Feb. 19, 2008**

(54) **VALVE-STEM MOUNTABLE TIRE
PRESSURE GAUGE**

6,374,666 B1 4/2002 Lemberger et al.
6,531,960 B1 3/2003 Gladstone et al.
6,911,903 B2 6/2005 Gladstone et al.

(75) Inventor: **Steven Petrucci, Cranbury, NJ (US)**

* cited by examiner

(73) Assignee: **Measurement Limited**

Primary Examiner—Antoine D. Davis

(**) Term: **14 Years**

(74) Attorney, Agent, or Firm—Howard IP Law Group, P.C.

(21) Appl. No.: **29/268,053**

(57) **CLAIM**

(22) Filed: **Oct. 27, 2006**

The ornamental design for a valve-stem mountable tire pressure gauge, as shown and described.

(51) **LOC (8) Cl. 10-04**

DESCRIPTION

(52) **U.S. Cl. D10/86**

(58) **Field of Classification Search** D10/83,
D10/86; 73/146—146.8; 116/34 R; 200/61.22,
200/61.25; 340/442—447

See application file for complete search history.

FIG. 1 is a perspective view of a valve-stem mountable tire pressure gauge showing my new design;

FIG. 2 is a front view thereof, a rear view being a mirror image thereof;

FIG. 3 is a right side view thereof, a left side view being a mirror image thereof;

FIG. 4 is a top view thereof; and,

FIG. 5 is a bottom view thereof.

The matter shown in broken lines is shown for illustrative purposes only, and forms no part of the claimed design.
